(57) **CLAIM**

We claim the ornamental design for a Y-arm cascade display for sheet goods, as shown and described.

DESCRIPTION

FIG. 1 is a side elevation view of a Y-arm cascade display for sheet goods of the present invention, the opposite side being a mirror image thereof.

FIG. 2 is a front elevation view of the Y-arm cascade display for sheet goods shown in FIG. 1, the back elevation view being a mirror image thereof.

FIG. 3 is a top plan view of the Y-arm cascade display for sheet goods shown in the previous Figures.

FIG. 4 is a bottom plan view of the Y-arm cascade display for sheet goods shown in the previous Figures; and,

FIG. 5 is a perspective view the Y-arm cascade display for sheet goods shown in the previous Figures.
